(57) **CLAIM**

The ornamental design for a vehicle hood scoop attachment, as shown and described.

DESCRIPTION

FIG. 1 is a top plan view of a vehicle hood scoop attachment showing my new design;

FIG. 2 is a perspective view thereof as seen from the upper front right;

FIG. 3 is a bottom view thereof;

FIG. 4 is a rear elevational view thereof;

FIG. 5 is a front elevational view thereof;

FIG. 6 is a left side elevational view thereof; and,

FIG. 7 is a right side elevational view thereof.

The broken lines in FIG. 1 is for illustrative purposes only and form no part of the claimed design.

The broken lines in FIG. 3 outline a portion of the bottom of the vehicle hood scoop attachment which is not visible during use and forms no part of the claimed design.
